US00D722417S

(12) **United States Design Patent**
Rogers et al.

(10) **Patent No.:** **US D722,417 S**
(45) **Date of Patent:** **** Feb. 17, 2015**

(54) **ROOT VEGETABLE PRODUCT**

(71) Applicant: **McCain Foods Limited**, Florenceville (CA)

(72) Inventors: **David M. Rogers**, Woodstock (CA); **John Aikens**, New Maryland (CA)

(73) Assignee: **McCain Foods Limited**, Florenceville-Bristol (CA)

(**) Term: **14 Years**

(21) Appl. No.: **29/489,733**

(22) Filed: **May 2, 2014**

Related U.S. Application Data

(62) Division of application No. 29/456,306, filed on May 30, 2013, now Pat. No. Des. 712,618.
